C. W. H. BLOOD.

FEED ROLL FOR PLANING MACHINES.

(Application filed June 26, 1901.)

(No Model.)

Fig. 1.

UNITED STATES PATENT OFFICE.

CHARLES W. H. BLOOD, OF BOSTON, MASSACHUSETTS, ASSIGNOR TO S. A. WOODS MACHINE COMPANY, OF BOSTON, MASSACHUSETTS, A CORPORATION OF MASSACHUSETTS.

FEED-ROLL FOR PLANING-MACHINES.

SPECIFICATION forming part of Letters Patent No. 690,383, dated December 31, 1901.

Application filed June 26, 1901. Serial No. 66,122. (No model.)

To all whom it may concern:

Be it known that I, CHARLES W. H. BLOOD, a citizen of the United States, residing at Boston, in the county of Suffolk and State of Massachusetts, have invented an Improvement in Feed-Rolls for Planing-Machines, of which the following description, in connection with the accompanying drawings, is a specification, like characters on the drawings representing like parts.

My invention is an improvement in planing-machines, and relates to a construction of the feed-roll for permitting the simultaneous feeding through the machine thereby with even feeding pressure of a plurality of boards or timbers of varying thicknesses.

More definitely stated, my invention consists in providing on an unyielding shaft a series of independent shells or rolls, each held downwardly by compression-springs which can yield toward said shaft for permitting the roll to yield to a thick timber or to an inequality thereof.

My invention in its preferred embodiment herein shown comprises various further details of construction, all of which will be more fully pointed out in the following description and thereafter further defined in the appended claims.

In the drawings, Figure 1 shows in side elevation my invention applied to an ordinary feed-roll shaft, parts being broken away and shown in section for clearness of illustration. Figs. 2, 3, and 4 are perspective views of certain constructional details which go to make up the present embodiment of the invention. Fig. 5 is a transverse vertical section taken on the line 5 5, Fig. 1.

It will be understood that my invention is applicable to any planing-machine or other machine where a yielding roll of this character is required, the shaft *a* being of such length and size as may be required for the purpose, having a journal end *a'* and suitable driving mechanism *a''*.

The feed-roll is made up of a plurality of shells or separate rolls *b*, preferably separated from each other by a separator *c*, which, as herein shown, is of special construction and

performs the twofold function of separating 50 or alining the rolls and retaining the spring-carrier, as will presently be described.

Within the shell or roll *b* is a driver *d*, keyed to the shaft *a*, and at the opposite ends of the driver are pressure-transmitting devices *e*, which comprise carriers *e'*, containing compression-springs *e''*, retained in the ends thereof, as is clearly shown in Figs. 4 and 5.

The roll or shell *b* and driver *d* are provided with coöperating lugs or teeth *b'* *d'*, respectively, spaced at intervals to permit the looseness or freedom of movement therebetween required to permit the shell to assume its different positions, as is clearly shown in Fig. 5.

It is not new to have a yielding shell-like roll *b* driven by engaging arms or teeth after the manner of an internal gear, and I do not therefore claim the same as my invention, the latter residing more particularly in the particular provision for securing the yielding action of the roll and, further, residing in the special construction by which enormous strength of parts is provided and great resistance is secured between the shell and driver, the springs and shell, the shaft and springs, and between the various coöperating parts of adjacent portions of the entire feed-roll.

Viewing Figs. 1 and 3, it will be observed that the ends of the driver *d* are undercut at *d'*, or, in other words, the teeth or arms *d'* thereof overhang said ends, so as to provide a housing for retaining the yielding pressure-transmitting device *e*, whose carriers *e'*, in the shape of segmental blocks, are held normally pressed tightly against the overhanging ends of the teeth *d'*. Preferably the undercut portion or housing *d'* is in alinement with a similar undercut housing or spring-retainer *c'*, formed in the separator *c*. The teeth *b'* of the shell *b* normally project between the teeth *d'* with their inner surfaces *b''* in supporting contact with the spring-carriers *e'*, the latter in such position being out of engagement with the shaft *a*, as is clearly shown in the left-hand section, Fig. 1, of the feed-roll, and when

a section of the feed-roll is required to yield, as is shown in the second section, Fig. 1, the teeth b' of the shell b force the lower part of the spring device e upwardly away from its seat in the housings c d^2 , as shown in Fig. 5.

From the above description it will be evident that a firm strong downward pressure is constantly maintained on the various sections each independently of the other, the device e not being capable of moving upwardly at its upper side, but being positively held at its upper side between the undercut portions of the driver and separator and only capable of yielding upwardly at its lower side when required to do so by the passage of an extra thickness of material to be treated. When thus required to yield, the upper portion of the member e remains practically unchanged at the instant of yielding, and the lower portion of said member is collapsed or forced upwardly against the resistance of the intervening springs e^2 , said lower part at such time moving away from the projecting ends of the teeth d' , which normally retain it, and reaching its upward limit when coming in contact with the shaft a , being thus forced upwardly solely by the shell b , whose teeth b' bear against it. To permit this movement, the depth of the teeth d' from their undercut side d^2 to their outer or peripheral side is less than the depth of the teeth b' , similarly as the carriers e are narrower than the distance between the shaft and the housing d^2 . It will be observed also that the drivers have a driving engagement with the shell b throughout practically the width of the latter, (see Fig. 1,) and also the construction is such that the engaging teeth of both shell and driver have considerable thickness, as well as the long engaging surface just mentioned, the result being great strength.

It has been my aim to produce as nearly a solid construction as possible, and yet permit the requisite yielding movement.

45 The driver is practically solid with the shaft, and the pressure-transmitting device is carried by said shaft entirely independently of the shell or roll b , the latter being simply a solid one-piece part, and all the parts are of a similar nature as far as possible, the entire arrangement being without complication of connected or dependent parts, excepting as the shell bears upon and is centered by contact with the pressure-transmitting device.

55 The pressure-transmitting device is so arranged, as is evident from Fig. 5, that the compressed springs exert their maximum effect in a downward direction, thereby co-operating with the downward driving effect or 60 "fighting" action of the contacting teeth 1 2 of the driver and shell in giving a maximum downward pressure.

The pressure-transmitting mechanism is carried by the shaft as distinguished from being carried by the shell, or, in other words, if the shell were removed entirely the device e would not be effected, but would still be re-

tained by the shaft, as it is held thereon by the driver, which is practically a part of the shaft.

70 Four carriers and a corresponding number of springs are usually sufficient for the pressure-transmitting device e ; but it will be understood that in this, as well as in all the various constructional details which I have described, I am not limited otherwise than as expressed in the claims.

Having described my invention, what I claim, and desire to secure by Letters Patent, is—

80 1. A feed-roll comprising a shaft, a driver mounted thereon, a shell surrounding said driver, said driver and shell having between them mutually-engaging driving portions, and yielding pressure-transmitting mechanism and means on said shaft, independent of said shell, for retaining said pressure-transmitting mechanism, the latter operating upon said shell.

85 2. A feed-roll comprising a shaft, a shell or roll, driving mechanism for driving said shell by said shaft, and yielding means carried independently of said shell for normally maintaining said shell concentric with said shaft and permitting it to yield eccentrically there- 95 to when required.

90 3. A feed-roll comprising a shaft, a shell or roll mounted thereon and movable transversely thereof, driving means for rotating said shell with said shaft, yielding pressure- 100 transmitting mechanism for normally maintaining said shell concentric with the shaft and permitting it to yield upwardly thereto when required, and means for preventing the upward movement with said shell of the up- 105 per part of said pressure-transmitting mechanism.

4. A feed-roll comprising a shaft, a shell or roll mounted thereon and movable transversely thereof, driving means for rotating said shell with said shaft, and compression spring mechanism carried independently of said shell for giving said shell a yielding downward pressure.

110 5. A feed-roll comprising a shaft, a shell mounted thereon and movable transversely thereof, a driver carried by said shaft, said shell and driver having engaging portions for loosely driving the former by the latter, and pressure-transmitting devices at the opposite 120 ends of said driver and retained thereby and capable of yielding toward said shaft for permitting an eccentric movement of the shell.

115 6. In a feed-roll, a driver, and a shell loosely driven thereby, said driver and shell each having radial teeth, and pressure-transmitting devices at the opposite ends of said driver, said pressure-transmitting devices being narrow and the teeth of the driver being integral with the driver from one of said pressure-transmitting mechanisms to the other, and the teeth of said shell being integral with the shell throughout their lengths.

125 7. In a feed-roll, a driver, and a shell loosely

driven thereby, said driver and shell each having radial teeth, and pressure-transmitting devices at the opposite ends of said driver, said pressure-transmitting devices being narrow and the teeth of the driver being integral with the driver from one of said pressure-transmitting mechanisms to the other and having overhanging portions at their ends for confining the pressure-transmitting mechanisms against movement away from the shaft, and the teeth of said shell being integral with the shell throughout their lengths.

8. A feed-roll comprising a shaft, a shell, a driver therefor, and an annular pressure-transmitting device carried independently of said shell capable of collapsing toward said shaft and held against movement away from said shaft.

9. A feed-roll comprising a shaft, a driver, a shell, and a pressure-transmitting compression device, said driver containing a housing for retaining said transmitting device and said shell having projecting portions normally engaging said transmitting device within said housing for moving said transmitting device inwardly upon a corresponding movement of the shell.

10. A feed-roll comprising a shaft and a series of shells or rolls, driving mechanism for driving said shells with the shaft, pressure-transmitting mechanism normally maintaining said shells concentric with the shaft and permitting them to yield independently eccentrically thereto, and separators carried by the shaft for separating said shells.

11. A feed-roll comprising a shaft, and a series of shells or rolls, driving mechanism for driving said shells with the shaft, pressure-transmitting mechanism normally maintaining said shells concentric with the shaft and permitting them to yield independently eccentrically thereto, and separators carried by the shaft for separating said shells, said separators having retaining portions for holding

said pressure-transmitting mechanism in normal position. 45

12. A feed-roll comprising a shaft, a shell, driving mechanism for the latter, and pressure-transmitting mechanism normally maintaining said shell concentric with said shaft 50 and permitting it to yield relatively thereto, and opposite housings or retaining portions on opposite sides of said pressure-transmitting mechanism for limiting the outward radial movement of the latter independently of the movement of said shell.

13. A feed-roll comprising a shaft, a shell or roll, a driver in driving contact with said shell, and pressure-transmitting mechanism, separate from said driver, consisting of carriers 60 adapted to be engaged by said shell, and springs yieldingly connecting said carriers.

14. A feed-roll comprising a shaft, a shell or roll, a driver in driving contact with said shell, and pressure-transmitting mechanism acting 65 independent of said driver, the latter consisting of segmental blocks, and springs interposed between and separating said blocks holding the same in engagement with said shell.

15. A feed-roll comprising a shaft, a shell or roll, a driver, said shell and driver having on their contiguous surfaces projecting teeth adapted to interlock for driving the shaft said teeth being broad and heavy and extending 75 longitudinally of and integral at their bases with said shell and driver, and means retained by the driver-teeth at each end thereof for normally maintaining said shell yieldingly concentric to the shaft. 80

In testimony whereof I have signed my name to this specification in the presence of two subscribing witnesses.

CHARLES W. H. BLOOD.

Witnesses:

GEO. H. MAXWELL,
EDITH M. STODDARD.

It is hereby certified that in Letters Patent No. 690,383, granted December 31, 1901, upon the application of Charles W. H. Blood, of Boston, Massachusetts, for an improvement in "Feed-Rolls for Planing-Machines," an error appears in the printed specifications requiring correction, as follows: In line 97, page 2, the words "she roll" should read *shell or*; and that the said Letters Patent should be read with this correction therein that the same may conform to the record of the case in the Patent Office.

Signed, countersigned, and sealed this 21st day of January, A. D., 1902.

[SEAL.]

F. L. CAMPBELL,
Assistant Secretary of the Interior.
